CLAIM

The ornamental design for a stand and counterbalanced support, as shown and described.

DESCRIPTION

FIG. 1 is a frontal perspective view of an embodiment of a stand for a counterbalanced support of the instant inventive concept.

FIG. 2 is a front elevation view of the stand of FIG. 1, the side views and opposing rear view being mirror images thereof.

FIG. 3 is a top plan view of the stand of FIG. 1.

FIG. 4 is a bottom plan view of the stand of FIG. 1; and, FIG. 5 is a frontal perspective exploded view of the stand of FIG. 1.
